UNITED STATES PATENT OFFICE.

WILLARD E. CHAMBERLAIN, OF NEW HAVEN, CONNECTICUT, ASSIGNOR TO THE NEW HAVEN CLOCK CO., OF NEW HAVEN, CONNECTICUT, A CORPORATION.

DEVICE FOR TIMING TIMEPIECES.

Application filed June 30, 1924. Serial No. 723,228.

To all whom it may concern:

Be it known that I, WILLARD E. CHAMBERLAIN, a citizen of the United States, residing at New Haven, in the county of New Haven and State of Connecticut, have invented a new and useful Improvement in Devices for Timing Timepieces; and I do hereby declare the following, when taken in connection with the accompanying drawings 10 and the characters of reference marked thereon, to be a full, clear, and exact description of the same, and which said drawings constitute part of this application; and represent, in

Fig. 1 an end view of one form which my improved device for timing time-pieces may assume; small, circular clock-movements, indicated by broken lines, being installed upon it.

Fig. 2 a broken view thereof in front elevation, looking in the direction of the arrow 2 of Fig. 1.

Fig. 3 an enlarged, detail, broken, sectional view, showing one of the movement-mounting sockets.

Fig. 4 an enlarged, detached, perspective view of one of the yielding starting-and-stopping fingers of the multiple, movement-starting-and-stopping unit.

Heretofore, in the manufacture of time-pieces, such as clocks and watches, they have been individually timed by running them for considerable periods in comparison with a master time-piece. The common practice has been for the "timer" to successively start a group of clocks or watches and, after running them for several hours or even days, to successively stop them. Since the movements are not started or stopped simultaneously, the result cannot be accurate. The practice described is tedious, time-consuming, expensive—both of labor and factory-space, and unsatisfactory in result, since the master-clock and the movements to be timed by it are not simultaneously stopped and started, which is indispensable to accurate comparison. The object of my present invention is to overcome the objections above recited and to enable the timing of time-pieces, which is one of the most delicate phases of the making of clocks and watches on a large scale, to be conducted rapidly, effectively and at a low cost.

With these ends in view, my invention consists in a device for timing time-pieces

comprising a movement-mounting unit adapted to have a plurality of time-pieces positioned upon it, and a multiple, movement-starting-and-stopping unit adapted to be manually shifted, and comprising a plurality of similar operating-members arranged to coact with a moving part of the several time-pieces positioned upon the movement-mounting unit.

My invention further consists in a device for timing time-pieces having certain details of construction and combinations of parts as will be hereinafter described and particularly pointed out in the claims.

In carrying out my invention as herein shown, I employ a movement-mounting unit comprising an inclined platform in the form of an installation board 5 having its lower edge beveled and secured by a hinge 6 to the forward edge of a baseboard 7. As shown, triangular braces 8, secured to the rear face of the board 5, rest upon the baseboard 7 to support the former with its weight of time-pieces. As shown, the board 5 is reinforced by a metal face-plate 9 upon which are superimposed parallel horizontal plates 10 and 11, each mounting, at regularly spaced intervals, groups of similar sockets 12 having bores 13. The specific construction, relative arrangement and number of these sockets will, of course, depend upon the character and size of the time-pieces to be regulated. The device chosen for illustration is designed for the timing of small, circular clock-movements having movement plates 14 and 15 and four extended pillars 16. For the mounting of such movements, I employ, as shown, groups of sockets, each group consisting of four sockets 12, these sockets being spaced apart exactly in accordance with the spacing of the pillars 16 of the movements in question. Since the particular character of the time-pieces timed forms no part of my invention, I have considered it sufficient to indicate the time-pieces illustrated by broken lines and to limit their illustration to their front and rear movement-plates 14 and 15, their pillars 16 and their balance-wheels 17. Such movements are readily mounted by registering their pillars 16 with the bores 13 of the sockets 12 of the respective groups of sockets, in which they are retained by gravity,

owing to the rearwardly-inclined position of the board 5. When the movements are

so positioned upon the said board, their balance-wheels 17 are brought into the paths of a corresponding number of yielding movement-stopping-and-starting fingers 27 consisting of light, sheet-metal strips, secured by screws 18 to the flattened upper faces of collars 19 adjustably attached by set-screws 20 to parallel rods 21—21 having sliding bearing in brackets 22 mounted in the lower edge of the superimposed socket-mounting plates 10. A coupling-bar 23, uniting the rods 21, provides for moving them simultaneously in both directions. The opposite ends of the said rods are provided with special collars 24 limiting their movement in one direction, while the coupling-bar 23 limits it in the other direction. The fingers 27, collars 19, rods 21 and coupling-bar 23 together constitute the multiple, movement-stopping-and-starting unit of my device. Preferably, this unit is shifted to the limit of its movement from right to left, prior to installing the clock-movements upon the inclined board or platform of the multiple, movement-mounting unit. Prior to any test, two previously-regulated master movements of the same type as those to be tested are mounted upon the installation board, such as the movements specially designated herein as 25 and 26.

Let it be supposed that a plurality of clock-movements have been installed upon the mounting-board 5, as well as the two master time-pieces 25 and 26, and that all of them are set to the same time and that all are held at rest by the engagement of the spring-fingers of the multiple, movement-stopping-and-starting unit with the respective balance-wheels of the several movements, including the master movements. Now a shifting movement of the stopping-and-starting unit, by using the coupling-bar 23 as a handle, from right to left, will simultaneously start all of the movements, including the master movements, the wiping engagement of the respective fingers with the respective balance-wheels giving the necessary starting impulse, after which the movements will run under their own spring power, the described movement of the stopping-and-starting unit from right to left being sufficient to clear the springs 21 from the balance-wheels 16, as shown in broken lines at the left in Fig. 2. All of the movements, having thus been simultaneously started, are allowed to run a predetermined length of time and are then simultaneously stopped by the operator (called the "timer"), who slides the stopping-and-starting unit in the opposite direction, i. e., from left to right, so as to re-engage the several fingers 27 with the several balance-wheels 21. In this way, all of the clocks, including the master clocks, are started together and all of the

movements, including the master movements, are stopped together, which has not been possible under any prior practice. The length of time allotted to running the movements will depend upon their character and the degree of accuracy desired, but it is very brief, compared with the length of time found necessary under the present practice of individual timing. After the movements have been stopped, they are compared with the master movements and their hair-springs taken up or let out proportionately, as they are shown to have run slower or faster than the master movements, this regulation of the hair-springs being done individually, by shifting the regulators, whatever their character, with which the movements are provided.

The operation of actually regulating the movements may be done before or after their removal from the device as may be found convenient and expedient. In the device illustrated, I have shown only two rows of movements, but it is apparent that the rods 21 may be lengthened or increased in number, the capacity of any individual device depending upon the character and size of the movements to be regulated.

I would, therefore, have it understood that I do not limit myself to the device shown and described, my invention being characterized by a device in which a plurality of similar time-pieces, of whatever character, may be stopped and started simultaneously, with one or more master time-pieces.

I claim:

1. A device for timing time-pieces having a multiple mounting-unit, providing for the installation upon it of a plurality of time-pieces, and having a multiple, movement-stopping-and-starting unit furnished with a plurality of stopping-and-starting members positioned to simultaneously start a plurality of time-pieces installed upon the said mounting-unit by engaging a member of their balance mechanisms with a wiping action, whereby the several time-pieces are simultaneously given a starting impulse.

2. In a device for timing time-pieces, a multiple mounting-unit having a plurality of similar groups of sockets arranged in accordance with the arrangement of the pillars of the time-pieces to be regulated, and also having a multiple, movement-stopping-and-starting unit comprising a reciprocatable bar carrying yielding fingers positioned upon it, so as to be simultaneously engaged with and disengaged from corresponding moving parts of the time-pieces installed upon the mounting-unit.

3. In a device for timing time-pieces, the combination with an inclined installation board, of a plurality of similar groups of sockets mounted thereupon for the recep-

tion of the pillars of the movements to be regulated, and a multiple, movement-stopping-and-starting unit consisting of a plurality of parallel rods coupled together at their ends and carrying a plurality of similar stopping-and-starting springs positioned to engage with moving parts of the time-movements so mounted and positioned.

In testimony whereof, I have signed this specification in the presence of two subscribing witnesses.

WILLARD E. CHAMBERLAIN.
